UNITED STATES PATENT OFFICE.

THOMAS F. RAINSFORD AND THOMAS C. WHITEHEAD, OF DETROIT, MICHIGAN, AS
SIGNORS TO THOMAS C. WHITEHEAD, OF DETROIT, MICHIGAN.

REFRIGERATING APPARATUS.

Application filed May 18, 1925. Serial No. 31,149.

This invention relates to refrigerating apparatus and more particularly to improvements in certain parts thereof.

The invention has particular reference to 5 improvements in the base or main support upon which the several parts of the apparatus are mounted whereby additional compactness and utility are obtained, the construction offering further possibilities, such 10 as cheapness in manufacture, durability and convenience in assembling. The invention further contemplates the association with a portion of the base, of a casing constituting a crank case, adapted to be secured to an up- 15 standing portion of said base and accurately aligned therewith whereby bearings may be provided in said casing and base part for supporting the crank shaft of the apparatus in axial alignment with the shaft of the motor 20 adapted to be supported upon the pedestal portion of said base.

The invention has as a further object, to 25 simplify, render more efficient, and improve generally arrangements of this general character, and the means for attaining all of the aforesaid objects as well as other advantages, and the details of one illustrative example of the invention will be made more apparent as 30 this description proceeds, especially when considered in connection with the accompanying drawings, wherein

Figure 1 is a view partly in vertical section and partly in elevation of an apparatus constructed in accordance with our invention,

35 Figure 2 is the top plan of the structure illustrated in Figure 1,

Figure 3 is a fragmentary sectional view taken substantially on the plane indicated by the line 3—3 in Figure 1, and

40 Figure 4 is an end elevation of the apparatus.

Referring now particularly to the drawings wherein like reference characters indicate like parts it will be noted that there is illustrated a base 10 upon which is mounted a radiator 11 which comprises vertical cooling tubes 12 and horizontal heat radiating or fin plates 13, these cooling tubes connecting at their upper ends with an upper header 14. Associated 50 with the radiator is a cooling fan 15 mounted

upon a shaft 16, one end of which is connected by means of a flexible coupling 17 to the shaft of a motor 18.

The base 10 is so constructed as to facilitate the correct mounting and spacing of the 55 radiator and motor, to provide one of the headers for the radiator and to furthermore cooperate in supporting the crank shaft 16.

To this end the base, which is preferably 60 an integral structure, is formed, at one end, 65 with an upwardly extending supporting platform or pedestal 19 having a horizontal surface parallel with but elevated with reference to the intermediate portion 20 of the base. The base is further provided with a plurality of feet or supporting legs 21, arranged at 70 each end as shown. The motor 18 is adapted to be supported upon pedestal 19 and secured in place, for instance, by bolts 22 threaded into pedestal support 19.

75 Formed integrally with the intermediate portion 20 of the base is a hollow compartment or chamber 23 constituting a header for radiator 11. For this purpose the lower wall of the chamber is provided with a threaded aperture 24 by means of which a conduit 25 is connected thereto, whereby the refrigerating fluid may be conducted to the evaporator. The upper wall of the chamber 23 is formed with apertures 26 whereby cooling tubes 12 80 of the radiator may have communication with header 23. The apertures 26 are preferably surrounded by upstanding bosses 27, the apertures 26 being bridged by plates 28 through which tubes 12 extend and to which said tubes 85 are anchored. Plates 28 rest upon bosses 27 and are rigidly secured in place by bolts 29 which pass upwardly through header 23 and are threaded into plates 28, the heads 30 of these bolts preferably engaging bosses 31 90 formed on the lower wall of header chamber 23.

The end of base 10 remote from pedestal 19 is formed with a lateral upwardly extending projection 32 which extends up beyond 95 the plane of the axis of crank shaft 16, as clearly shown in Figure 1. The projecting portion 32 of the base is formed with laterally extending ribs 32' at the vertical edges thereof which strengthen and reinforce projection 100

- 32, these ribs merging into legs 21 at the bottom thereof. This upstanding projection is formed with a lateral horizontally extending sleeve 33 which constitutes a bearing for shaft 16, a bushing 34, preferably of some composition material, being interposed between sleeve 33 and shaft 16. It will be noted that sleeve bearing 33 is of a relatively great length whereby a considerable longitudinal support is afforded to shaft 16 and inasmuch as projection 32 and sleeve 33 are formed integrally with base 10 it follows that shaft 16 will be correctly supported and held in parallel alignment with said base.
- 15 One face of projection 32 is formed with a bearing surface 35 and an immediately adjacent continuous shoulder or collar 36. Surface 35 and collar 36 are adapted to be engaged by the periphery 37 of a casing 38 constituting a crank case into which shaft 16 extends, as shown clearly in Figure 1. The surface 35 and collar 36 correspond to the peripheral contour of casing 38 and by properly machining the abutting surfaces of projection 32 and casing 38 these parts may be properly aligned and the casing 38 may be rigidly connected to projection 32, as for instance by bolts 39.
- The wall of casing 38 remote from projection 32 is formed with a sleeve 40 constituting a bearing for the end of shaft 16, a bushing 41, preferably of some composition material, being inserted between shaft 16 and bearing sleeve 40. Bearing sleeve 40 is in alignment with bearing sleeve 33 formed on projection 32, and inasmuch as casing 38 is accurately assembled with reference to projection 32 these bearings may be formed in accurate alignment to properly support shaft 16. It will be furthermore noted that shaft bearings 33 and 40 are in axial alignment with the shaft of motor 18 so that shaft 16 may be connected to the motor shaft in the manner aforesaid.
- 45 Casing 38, as has been previously mentioned, constitutes a crank case and houses the fly wheels 42 carried by shaft 16. The casing 38 is preferably formed with a cylinder like extension 43 constituting the cylinder of a compressor in which is reciprocally mounted a piston 44 operated by connecting rod 45 connected to a cam portion of shaft 16. A reciprocal sleeve valve 46 is associated with the compressor and controlled by suitable operating arm 47 also connected to a cam portion of shaft 16. The upper end of the compressor communicates with the upper end of the radiator by suitable conduit 48.
- Casing 38 is adapted to contain a supply of lubricant which will be splashed or thrown upwardly by fly wheels 42 for feeding the same to a suitable lubricating system for the apparatus. In order to make the interior of the casing 38 accessible the lower wall thereof is formed with a threaded aperture 49, this

aperture being surrounded by a boss 50 whereby the threaded area may be increased. Associated with the threaded aperture 50 is a plug 51, formed preferably of a suitable composition material and designed, when 70 screwed home, to lie flush with the outer surface of casing 38 and also preferably with boss 50 on the inner surface of casing 38. By forming plug 51 of a composition material the necessity for gaskets is eliminated. 75 The plug is preferably formed with an irregular shaped socket which may be engaged by a suitable tool for inserting or removing the plug.

The mode of operation of the device will 80 be readily understood. After the refrigerant is compressed in the cylinder 44 it is introduced in to the radiator 11 through the conduit 48 where it is condensed and passed through the conduit 25 to the usual expansion 85 coils (not shown), which are usually placed in a chamber to be refrigerated. After absorbing the heat in the chamber the refrigerant is conveyed back to the compressor and the cycle repeated. 90

From the foregoing it will be readily apparent that the herein described construction offers means for mounting the parts of the apparatus whereby a compact assembly results. Furthermore the assembling of the 95 apparatus is facilitated as the parts may be quickly attached and easily aligned. We propose casting base 10 whereby this portion of the apparatus may be cheaply and easily manufactured, and by merely machining the 100 engaging parts of projection 32 and casing 38 these parts may be properly united and aligned to correctly support the crank shaft. The provision of header 23 not only eliminates the necessity for providing a separate 105 lower header for the radiator but affords means for mounting and properly spacing the radiator with reference to the remaining structure. Furthermore projection 32 which in turn supports casing 38 constitutes in part 110 a support for the compressor which in the illustrative embodiment herein shown is formed in an extension of casing 38.

While the invention has been shown and described herein in some detail, it will be readily 115 apparent that various modifications in the specific structure illustrated may be resorted to without departing from the spirit and scope of the invention and to this end reservation is made to make such changes as may 120 come within the purview of the accompanying claims.

What we claim as our invention is:

1. In a refrigerating apparatus including a radiator, a motor and a crank shaft, the 125 combination therewith of a base formed with a support for said motor, a hollow portion constituting a header for said radiator and an upwardly extending projection, a casing secured to said projection, and bearings 130

formed in said projection and casing for securing said crank shaft, said bearings being aligned with the shaft of said motor.

2. In a refrigerating apparatus including a condenser, a motor and a crank shaft, the combination with a cast base formed with a support for said motor, a portion constitut-

ing a header for said condenser, and a projection forming a bearing for said crank shaft.

In testimony whereof we affix our signatures.

THOMAS F. RAINSFORD.
THOMAS C. WHITEHEAD.
